UNITED STATES PATENT OFFICE.

GUSTAF ÖRSTRÖM, OF STOCKHOLM, SWEDEN, ASSIGNOR TO AKTIEBOLAGET GERH. AREHNS MEKANISKA VERKSTAD, OF STOCKHOLM, SWEDEN, A CORPORATION OF SWEDEN.

FOLDING DEVICE FOR BAG OR CAPSULE MAKING MACHINES.

1,425,044.

Specification of Letters Patent. Patented Aug. 8, 1922.

Application filed September 14, 1920. Serial No. 410,217.

To all whom it may concern:

Be it known that I, GUSTAF ÖRSTRÖM, a subject of the King of Sweden, residing at Palsundsgatan 7, Stockholm, in the Kingdom of Sweden, have invented certain new and useful Improvements in Folding Devices for Bag or Capsule Making Machines, of which the following is a specification.

This invention relates to a folding device for bag making machines of the type, in which a blank of paper or the like is wound round a mandrel, moved in an endless path, by two reciprocating folders, between which the said mandrel forces the blank. According to this invention the said machines are provided with presser rollers, which bear against two opposite sides of the mandrel and keep the paper tight against the same. Preferably, a third roller co-operates with the said rollers in order to hold the paper-blank against the mandrel, while the folding operation is effected. Preferably, rollers are also provided, which after the end flaps of the capsule have been folded and pasted together actuate simultaneously the said flaps and two sides of the capsule, thus rendering sharp the edges of the capsule.

In the accompanying drawings a paper-bag making machine is shown, provided with a folding device arranged in accordance with this invention. Figs. 1 and 2 show the folding device viewed from two different sides; only such parts of the machine are shown as are necessary for the understanding of the invention. Figs. 3 to 5 inclusive show diagrammatically the mode of operation of the folding device, while Fig. 6 also shows a folding device for the end flaps of the capsule and a set of pressure rollers for rendering sharp the end edges of the capsule. Figs. 7 and 8 show viewed from one end and from one side respectively presser rollers for rendering sharp the edges of the capsule at the folded end flaps.

1, 1 are the mandrels, round which the paper-blanks are folded. The said mandrels are carried by a disk or by arms fixed to a shaft 2, rotated in the direction, indicated by the arrow, or to a chain or the like moved in an endless path. The paper-blank 3, provided with paste at suitable parts, is placed by any suitable means on two top-folders 4 and 5 and in the position, shown in Fig. 3.

One of the mandrels 1 then moves downwards through the space between the said folders 4 and 5, bringing with itself the paper 3 so that its side flaps are bent upward, as shown in Fig. 4. During the said operation two rollers 6 and 7, according to this invention, bear against the vertical sides of the mandrel and forces the paper 3 against the mandrel, as shown in Fig. 4, so that it fits snugly to the sides of the mandrel. As the mandrel 1 has passed between the folders 4 and 5 to the position shown in Fig. 4, the mandrel stops and the folder 4 forces downward against the mandrel one of the flaps of the paper, the other flap being then folded by the folder 5, as shown in Fig. 5, the said flaps preferably having the same length.

After the paper has been folded round the mandrel 1 in the described manner, a presser 8 is forced against the flaps of the paper in order to ensure the pasting together of the said flaps. The said presser 8 partakes in the rotary motion of the mandrel and is then moved from the mandrel in order to permit the capsule formed by the paper to be moved from the mandrel, after the end flaps have been folded, which may be effected in any suitable manner.

While the paper is thus folded round the mandrel by the rollers 6 and 7, the said rollers evidently have no tendency of displacing the paper or moving one of its vertical branches upward. Besides the paper is smoothly placed on the mandrel.

According to this invention a third roller 9 is provided, which at the starting of the folding operation has the position, shown in Fig. 3, and then holds the paper 3 against the lower side of the mandrel 1, while the mandrel moves downwards between the rollers 6 and 7 and the paper is folded. The roller 9 is forced downward by the mandrel, while bearing against its lower side, and after the folding has been finished, the roller 9 moves upwards along the side of the mandrel 1, as shown in Fig. 6. After the mandrel has passed the roller 9, the latter is moved upwards into the position shown in Fig. 3, ready to hold the next paper-blank against the subsequent mandrel, passing between the rollers 6 and 7.

The said rollers 6 and 7 are mounted on

pins, fixed to arms 10 and 11 respectively, Figs. 1 and 2, which are pivoted at 12 to a bracket 13. A spring 14 connects the arms 11 and forces the rollers 6 and 7 against 5 the mandrel 1 passing between the same. In order to fix the inner position of the rollers 6 and 7 the said arms 10 and 11 are provided with downward extending projections 15 and 16, bearing against adjustable screws 17 and 18 respectively, provided 10 in the bracket 13.

Roller 9 is mounted on a pin fixed to an arm 20, pivoted at 21 to the frame of the machine and acted upon by a spring 15 22 fixed to the said frame. The said roller 9 forms a very simple device for holding the paper against the mandrel, no cam disk or the like being necessary for operating the same.

20 By means of the said rollers 6, 7 and 9 unobjectionable bags may be manufactured. The flaps at the one end of the capsule are then folded and pasted together. This is effected for instance by the means shown in 25 Fig. 6. 99 is a stationary tongue. As the capsule is moved with the mandrel 1 the flap at one of the short sides of the capsule is folded by the said tongue 99. A second tongue 92 is carried by a two armed lever 30 145, which is swingable on a pin 144 and acted upon by a spring and a cam disk, not shown. As the said tongue 92 is moved toward the left, it folds the flap at the opposite short side of the capsule. The other 35 side flaps of the capsule are then folded by stationary folders 100 and 101, respectively, consisting of plates which are located at opposite sides of the path of the capsule and the acting surfaces of which success- 40 sively extend inwards over the path of the capsule, so that they bend the flaps of the capsule. The flap last bent inwards may be provided with paste in any suitable manner, for instance as stated in the U. S. Letters Patent No. 1,879,254, so that it sticks 45 to the other flaps. After the end flaps of the capsule have been folded and pasted together the capsule is subjected to the action of three spring actuated presser rollers 50 165, 166 and 167 in order to procure sharp edges at the end of the capsule. The mandrel 1 with the capsule passes between the said rollers, which then bear against the end

flaps and two opposite sides of the capsule. In this manner the capsule gets a very neat 55 appearance and any tendency of the flaps to get loose is removed.

The presser rollers 165, 166 and 167, are also shown in Figures 7 and 8. The roller 165 is journalled in a fork 168, the shaft 60 169 of which is slidably mounted in bearings, one 170 being shown and is actuated by a spring. Rollers 166, 167 are journalled in arms 171, 172, pivoted to the fork 168 and connected by a spring 173. Suitable 65 abutments limit the movements of the rollers inwards toward one another.

Capsules etc. made in machines arranged as stated above may be used for packing different materials, such as matches, cigarettes etc. The mandrels 1 and pressers 8 and parts moving the same step by step and also the top folders 4 and 5 do not belong to the present invention and for that reason are not more closely described. 75

I claim:

1. In a machine for making bags, capsules or the like from blanks of paper or similar material the combination with mandrels moving in an endless path and reciprocating top folders, between which the mandrel passes and by which the blank is folded round the mandrel, of rollers, bearing against opposite sides of the mandrel and forcing the blank against the said sides, and of a roller holding the blank against the mandrel during the folding operation.

2. In a machine as stated in claim 1 the arrangement that the roller holding the blank against the mandrel is carried by a swingable arm actuated by a spring.

3. In a machine of the art stated in claim 1 and provided with means for folding the end flaps of the capsule, the provision of presser rollers between which the mandrel together with the folded paper passes for rendering sharp the end edges of the capsule.

In testimony whereof I have affixed my 100 signature in presence of two witnesses.

GUSTAF ÖRSTROM.
